CLAIM

The ornamental design for a body pouch, as shown and described.

DESCRIPTION

FIG. 1 is a rear perspective of a body pouch showing my new design, it being understood that the broken lines are for illustrative purposes only and form no part of the claimed design;

FIG. 2 is a right side view, the left side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

FIG. 5

FIG. 3

FIG. 4

FIG. 6

FIG. 2

FIG. 1
